UNITED STATES PATENT OFFICE.

REUBEN A. SIVARD, OF OKLAHOMA, OKLAHOMA, ASSIGNOR OF ONE-HALF TO EDWARD TAYLOR, OF OKLAHOMA, OKLAHOMA.

GUITAR.

1,317,830.

Specification of Letters Patent.

Patented Oct. 7, 1919.

Application filed March 11, 1918. Serial No. 221,698.

To all whom it may concern:

Be it known that I, REUBEN A. SIVARD, a citizen of the United States, residing at Oklahoma city, in the county of Oklahoma and 5 State of Oklahoma, have invented certain new and useful Improvements in Guitars, of which the following is a specification, reference being had to the accompanying drawings.

10 The invention pertains to improvements in stringed musical instruments, and more especially to those of the guitar or mandolin class.

The object of the invention is to provide 15 an instrument of this class on which harmonic chords may be more easily fingered.

Figure 1 of the accompanying drawings is a plan view of the improved instrument.

Fig. 2 is an enlarged reproduction of an 20 upper portion of Fig. 1, but showing the instrument strung single instead of double.

Fig. 3 is a sectional view on still larger scale, taken on the line 3—3 of Fig. 2.

Fig. 4 shows a staff on which is indicated 25 the tuning of the strings of the instrument.

Like characters of reference designate like parts in all the figures.

The instrument includes the body H, neck I, tuning-head J, tail-piece K, tuning-pins 30 L, strings G, D, A, and E, bridge M, and nut O.

In construction, assemblage, and function, the parts thus described do not differ materially from those found in the common 35 guitar, except that the strings are tuned differently.

In carrying out the object stated, the strings of the instrument are tuned in fifths, for example, to the pitches G, D, A, and E, 40 like those of the violin or mandolin and as indicated in Fig. 4; the strings being designated on the drawings by their pitch letters.

The instrument may be strung double like the common mandolin, as shown in Fig. 45 1, or single, as shown in Fig. 2.

The finger-board surface P of the neck I is provided with frets, which are spaced chromatically from the nut O and numbered consecutively from 1 to 13.

50 It will be noted that while the instrument is tuned in fifths, the vibrating portions of the "open" strings are not the same length.

The bridge M, however, is the rear limit of the vibrating portion of all strings, and the vibrating portion of the first or G string 55 extends entirely to the nut O.

The second or D string is permanently held down on the second fret 2 by a block Q which is inlaid in the finger-board surface P of the neck I as best shown in Fig. 3, so 60 that the vibrating portion of said string is between said fret 2 and the bridge M.

The third or A string is likewise permanently held down on the fourth fret 4 by a block Q; and the fourth or E string is held 65 down permanently on the sixth fret 6.

The D, A, and E strings pass loosely through the space R in the neck I under the blocks Q, so that they may be tuned and kept at proper pitch by the tuning-pins L. 70

With the strings tuned in fifths, and with the vibrating portions of the second, third, and fourth strings permanently limited at the second, fourth, and sixth frets, respectively, it is found that common chords in 75 practically any key can be fingered more easily and with less practice than on the guitar as commonly strung and tuned.

For example, take the tones G, D, B, and G which are used in the G chord in their 80 order upward. In this chord, G and D are open strings and require no fingering; and with the fingers reaching across the finger-board from the left the tone B is produced by bringing the A string down onto the 85 sixth fret with the third finger, and the upper tone G by bringing the E string down onto the ninth fret with the first or index finger.

Again, take the tones C, G, C, and E which, 90 in their order upward form a C chord which will harmonically follow the G chord. In this chord, the fundamental tone C is produced by bringing the G string down onto the fifth fret with the third finger; the 95 next tone G, by bringing the D string down onto the seventh fret with the second finger; the next tone C by bringing the A string down onto said seventh fret with the first finger; and the next or upper tone by leaving the upper or E string open.

In fingering the D chord, which may appropriately follow the C chord in the key of G, the tones D and A are produced by

leaving the D and A strings open and by bringing the E string down onto the eighth fret with the first finger.

The three chords named are fingered with the hand and fingers in an easy position, and it is found that none of the many chords used in different keys requires the fingers to be placed in an awkward or cramped position.

10 Having thus described the invention, I claim:

1. A stringed instrument of the class described, having a bridge and nut and a finger-board provided with frets chromatically spaced from said nut, two strings supported by the bridge and nut, and means carried by the finger-board and holding one of the strings down permanently in contact with the second fret, the strings being tuned a fifth apart.

2. A stringed instrument of the class described, having a bridge and nut and a finger-board provided with frets chromatically spaced from said nut, three strings supported by the bridge and nut, means carried by the finger-board and holding the second string permanently in contact with the second fret, and means carried by the finger-

board and holding the third string permanently in contact with the fourth fret, the strings being tuned a fifth apart.

3. A stringed instrument of the class described, having a bridge and nut and a finger-board provided with frets chromatically spaced from said nut, four strings supported by the bridge and nut, means carried by the finger-board and holding the second string permanently in contact with the second fret, means carried by the finger-board and holding the third string in contact with the fourth fret, and means carried by the finger-board and holding the fourth string in permanent contact with the sixth fret, the four strings being tuned in consecutive intervals of a fifth.

4. A stringed instrument of the class described, including a bridge, a nut, a finger-board provided with frets, and a block permanently inlaid in the finger-board to hold a string down on one of the frets, there being a passage in the finger-board under said block through which the string may freely pass.

Witness my hand this —22— day of February, 1918.

REUBEN A. SIVARD.
